CLAIM

I claim the ornamental design for the napkin dispenser, as shown and described.

DESCRIPTION

FIG. 1 is a partially elevated, angled view of the napkin dispenser.

FIG. 2 is a front view of the napkin dispenser shown in FIG. 1.

FIG. 3 is a side view of the napkin dispenser shown in FIG. 1.

FIG. 4 is a back view of the napkin dispenser shown in FIG. 1.

FIG. 5 is a top view of the napkin dispenser shown in FIG. 1; and,

FIG. 6 is a bottom view of the napkin dispenser shown in FIG. 1.

The broken-line disclosure in the views is for illustrative purposes only and forms no part of the claimed design.

1 Claim, 5 Drawing Sheets
